UNITED STATES PATENT OFFICE

KIRK HIMROD, OF CHICAGO, ILLINOIS, ASSIGNOR TO THE INTERNATIONAL
TYPAL TELEGRAPH COMPANY, OF DETROIT, MICHIGAN.

PRINTING-TELEGRAPH.

SPECIFICATION forming part of Letters Patent No. 624,487, dated May 9, 1899.

Application filed March 25, 1898. Serial No. 675,121. (No model.)

To all whom it may concern:

Be it known that J. KIRK HIMROD, a citizen of the United States, residing at Chicago, in the county of Cook and State of Illinois, have 5 invented a certain new and useful Improvement in Printing-Telegraphs, of which the following is a specification.

My invention relates to printing-telegraphs employing the system used in the printing-telegraph of Baudot, wherein there are transmitted for each character over a single wire a series of electrical impulses of substantially equal duration, (five or more,) some of one polarity and some of the other polarity, each 10 character being distinguished from all other characters by a particular permutation of the impulses, and wherein these impulses act upon a selecting mechanism at the receiving end of the line and so adjust it as to cause 15 the operation of the printing mechanism to print the particular character.

My object is to produce an apparatus of this character which will combine great speed, certainty of operation, and durability and 20 will provide for the transmission and reception of a large number of characters.

In general my apparatus consists, first, of a transmitter having either an individual-key keyboard, like a type-writer, and which upon 25 the actuation of a particular key transmits for each character impulses of the kind already referred to, or having, as suggested by Baudot, a combination-key keyboard comprising a number of keys (five or more) depending upon the electrical impulses and 30 which are adapted to be manipulated by the operator in the proper combinations to transmit the correct permutation of impulses for the character desired; second, a relay receiving 35 these impulses and controlling the local circuits; third, a distributor controlled by the relay and distributing the current of the local battery; fourth, a selector acted on by the distributed local impulses, so as to translate 40 into a different resulting effect each different permutation of the impulses, and, finally, a printing or other desired mechanism whose 45 action is controlled by the selector.

While the apparatus is particularly designed for printing-telegraphs, it is evident that the principle of construction employed

in the transmitter, relay, distributor, and selector may be utilized for type-writing machines or for any other purpose where it is desired to select and operate at a distance 55 any one of a large number of devices.

Before entering upon a description in detail of the apparatus with reference to the drawings I will explain its general characteristics in order that the specific description may be 60 more readily understood.

If an individual-key-keyboard transmitter is employed, as is preferable, it is provided with a number of keys mounted upon levers, and the depression of each key shifts from 65 the normal position one or more pole-changers of a series of five or more pole-changers. Since five impulses give a sufficient number of characters for the purpose of a printing-telegraph, I prefer to employ five pole-changers 70 for that purpose. If a combination-key-keyboard of the Baudot type is employed, five keys only will be used, each adapted and arranged to shift from the normal position one of the pole-changers. By depressing one or 75 more of these keys in proper combination the desired permutation of impulses will be obtained to correspond with the character desired. The pole-changers, as will be understood, are connected normally so as to transmit when put in connection with the line impulses of one polarity—for illustration, positive impulses. The effect of the depression of a key in an individual-key-keyboard machine or of depressing one or more of the keys 80 in the case of a combination-key-keyboard transmitter of the Baudot type is to shift one or more of these pole-changers so as to transmit one or more negative impulses, and it is by the permutations of the five impulses that 85 the different characters are distinguished. Instead of employing one set of pole-changers 90 acted upon by all the keys and requiring the performance of a sequence of operations set up by one adjustment of these pole-changers before another adjustment can be produced by a different key or by the operation of a 95 different combination of keys, I employ a number of these sets of pole-changers, (five in each set.) Two or more of such sets may be 100 employed; but I have found that six of such sets is a convenient number, and I prefer to

place these in three paths of rotation, two sets in each path. These six sets of pole-changers are movable successively into relation with the keys, one set being always in position to be operated on by all of the keys. To secure this motion, the pole-changers may be mounted upon one or more drums rotating beneath the key-levers by an intermittent motion controlled by an escapement, so as to bring at each position of rest one set of pole-changers into position to be operated upon by the keys. Extending across beneath all of the key-levers are a number of tilting bars, the number corresponding with the impulses of each set and being, for the purpose of a printing-telegraph, five. In the case of an individual-key-keyboard transmitter these tilting bars are engaged by selecting-teeth on the key-levers, each key-lever when depressed depressing one or more of the bars, according to the permutation which distinguishes the particular character. In the case of a combination-key-keyboard transmitter of the Baudot type, however, the tilting bars may be connected directly with the five keys, the desired permutation distinguishing the particular character being obtained by depressing the keys in the same permutation or combination. The five tilting bars have hung from them a number of sets of five fingers corresponding with the number of paths of rotation occupied by the pole-changers, so as to act upon any one of the six sets of pole-changers which may be in position for operation. Consequently the depression of any key in the case of an individual-key-keyboard machine or the depression of the desired combination of keys in the case of a combination-key-keyboard transmitter of the Baudot type pushes downwardly the same pole-changing fingers of the several sets carried by the tilting bars, thus acting on the set of pole-changers which happens to be uppermost. If the several sets of pole-changers were all located in the same path of rotation, only one set of selecting fingers on the tilting bars would be required. Another tilting bar passing beneath all the key-levers operates the escapement, so that the effect of depressing a key-lever or of depressing the particular combination of keys is to shift the pole-changers of one set and rotate all the pole-changers, so as to bring another set uppermost. This rotation also brings the pole-changers successively into connection with the line, and by a further movement and by means of stationary combs the pole-changers are returned to their normal position. To furnish power for rotating the shaft turning the pole-changers, I prefer to employ an electric motor having a surplus of power and use it to wind up a spring-barrel which is connected with the shaft, and I employ a circuit-controller which opens and closes the circuit of the motor, so as to maintain an approximately uniform stress of the driving-spring. The thirty pole-changers are connected through rubbing con-

tacts with wires extending to segments of a sunflower or equivalent means for distributing the impulses to the line. The contact-plates of the sunflower connected with the pole-changers of one set follow those connected with the pole-changers of another set in the same order in which the pole-changers are brought in position for operation by the keys. Between the plates of the sunflower which are connected with the pole-changers are other plates connected with earth, so that the line is grounded after each impulse, or this grounding may take place only after each set of five impulses, the purpose being to complete the line to ground for discharging it. A trailer-arm, which operates on the sunflower and is connected with the line, may either be rotated by the shaft which rotates the pole-changers or be operated by independent motive devices. If operated by the shaft referred to, it is capable of movement independent of that shaft and at a different rate by being connected with the shaft by a spiral spring and being retarded in its movement by means of a fly-wheel. By this means, although the motion of the shaft is intermittent, that of the trailer operated thereby may be continuous and approximately uniform. The fly-wheel is connected with its spindle by a pawl and ratchet, so as to permit of any overthrow without straining the parts. If the trailer-arm is operated by independent motive devices, the latter will be regulated to drive the trailer-arm with a continuous and approximately uniform movement. The advantages of this transmitter over anything heretofore proposed are numerous. The operation of the keyboard is made independent of the working of the line, and if the trailer is adjusted to have a uniform speed of rotation as great as the average speed of the operation, including pauses, the operator may work the keys in advance of the operation of the line and as rapidly as he sees fit, since the effect of working the keys is simply to shift in succession the different sets of pole-changers, these being connected with the line subsequently by the operation of the trailer. Not only is the operator enabled to work with great rapidity and without waiting for the pole-changers to be brought in connection with the line between the depression of keys transmitting successive characters, but since the intermittent action of the operator is translated into a continuous and uniform operation of the line the line is not idle at any time, and a greater length of time is therefore provided for the sending of the line impulses and the operation of the receiving apparatus, thus conducing to reliability.

For my relay I may use any suitable polarized device in which the positive and negative impulses will produce different mechanical effects—such, for instance, as a pair of Hughes magnets wound oppositely and connected in series or in multiple in the line. The positive impulses cause the release of the armature of

one of these magnets, while the negative impulses cause the release of the armature of the other magnet. The first of these magnets, which I will call a "positive" relay, closes a local circuit when the armature is retracted and advances the distributer, about to be described. The negative relay closes two circuits, one of which is the circuit for advancing the distributer and the other of which is a circuit through the distributer switch-arms to that magnet of the selector which is in connection with the segment of the distributer upon which a switch-arm is at the time in contact. In the local distributer-advancing circuit I preferably place two magnets, which operate in the same time as the distributer-advancing magnet and which serve to return with a quick and positive movement the relay-armatures to their attracted positions. The advantages of this form of relay are numerous. It is exceedingly sensitive and is capable of great speed of operation. It is also positive in its action, because the restoring-magnets, being made to act in the same time as the other local magnets, make certain that the relay-armatures will not return to their attracted positions until the local work is done. The distributer has a shaft which advances by a step-by-step movement, advancing one step for each line impulse, whether positive or negative. The shaft carries a switch-arm or trailer, which travels over a circular commutator composed of ten plates insulated from each other. Five of these plates are connected in succession with the five magnets of one division of the selector, about to be described, and the other five plates are connected with the five magnets of the other division of the selector. The local circuit to these ten magnets, which is closed by the negative relay, passes through the switch-arm and through the plate upon which it rests. The five magnets of each of the two sets of selector-magnets being operated only by the negative line impulses are energized for each set of five impulses corresponding to a character to the number and in the order of the negative impulses of the particular set. They act upon two divisions of the selector, each set of five selector-magnets adjusting its division of the selector in accordance with the negative line impulses and while the distributer switch-arm is passing through one-half of the distributer-plates. During this time the other division of the selector is performing the functions of printing and restoring. For these purposes the distributer-shaft carries two other rotating switch-arms, one of which closes the printing-circuit through the selector whose magnets are not being acted on by the distributer and the other of which subsequently closes a restoring-circuit for restoring the parts of this division of the selector to their normal positions. These two circuit-controllers divide between them the entire time which is occupied in setting up the permutation on the other division of the selector. A greater time is preferably given to the printing-circuit, which may occupy two-thirds of the time, while the restoring-circuit occupies one-third of the time. The distributer is also provided with an automatic restoring device which, should any failure of operation occur—for instance, in the mutilation of a character—leaving the distributer switch-arm in an intermediate position, will advance the switch-arm to the starting-plate of one or the other of two sets of plates carried by the distributer. The distributer has numerous advantages, arising from distributing the impulses between two sets of selector-magnets, thus enabling the entire time occupied by a set of impulses on the line to be utilized in establishing the permutation of one division of the selector which is characteristic of the particular signal and also arising from enabling the same time to be wholly occupied in the operation of the printing mechanism and in the restoration of the parts at the other division of the selector.

For my selector I employ a purely electrical device. Each division of the selector is composed, preferably, of thirty-one sets of six contact-plates, the plates of each set being placed in line and having their ends approaching, so as to form between the ends of the plates of each set five breaks, all of which it is necessary to bridge over to establish the circuit through the plates of a set. The different sets of plates are arranged side by side in a frame, the end plates at one end of all the sets being connected together electrically by a cross-plate and at the other end being separated electrically and connected to different wires, so as to form thirty-one different and independent possible circuits. The five breaks in the thirty-one sets of plates are arranged in line, and beneath these are placed five rock-shafts carrying five bars of insulating material which are in contact with the adjoining ends of the plates. These bars carry metal bridging-plates, which have an arrangement in accordance with the required permutations. These bars are shifted independently in one direction by the five selector-magnets and may be simultaneously restored to their original position by a single restoring-magnet. The movement of the distributer switch-arm over the five plates connected with these five magnets operates one or more of the selector-magnets, according to the number and arrangement of the negative impulses, the positive impulses having no effect upon the selector-magnets. The result of the reception of a complete set of five impulses representing a character is to close the five breaks through one, and only one, of the thirty-one sets of selector-plates. This being accomplished the distributer begins to act upon the five plates connected with the magnets of the other division of the selector, and while setting up the other division of the selector it closes the printing-circuit to the division of the selector already set up, and this printing-circuit

cuit is completed through the particular path which is closed at this division of the selector and causes the printing mechanism to be operated to print the particular character. The restoring-magnet is then brought into circuit and restores the one or more cross-bars of the selector to their normal position. Heretofore mechanically-operating selectors have been provided, but these are inferior to my electrical selector, which is capable of greater speed of operation.

The printing mechanism which I employ may have a construction similar to an ordinary type-writer, each type-bar being operated by a single magnet. Instead of this arrangement the printing mechanism may be provided with a single powerful magnet, which operates all the type-bars, effecting the printing, advancing the carriage, &c. In the latter case the particular type-bar which is operated by any movement of the printing-magnet is selected by a small magnet, one for each type-bar, which is in the same circuit as the printing-magnet and which moves a hook into line with a cross-bar operated by the printing-magnet. The thirty-one circuits of each division of the selector are connected with thirty-one small selecting or operating magnets at the type-writer, and if a single printing-magnet is used in connection with small selecting-magnets the said printing-magnet may be placed in the return-circuit of the thirty-one selecting-magnets. Since the small selecting-magnets operate more quickly than the printing-magnet, the effect of closing the printing-circuit is to cause the hook of one of the type-bars to be moved into position, and immediately thereafter the printing-magnet acts and depresses the particular type-bar. This specific form of printing mechanism has the advantage that the selecting-magnets may be small, since they have little or no work to perform, while the entire work of printing is performed by a single powerful printing-magnet.

In the accompanying drawings, forming a part hereof, Figure 1 is a plan view of the transmitter, showing the employment of an individual-key keyboard similar to a type-writer; Fig. 2, a plan view of a part of the same, illustrating a combination-key-keyboard transmitter of the Baudot type; Fig. 3, a section on the line 3 3 of Fig. 2; Fig. 4, a horizontal section of the transmitter, taken beneath the key-levers and tilting bars; Fig. 5, an end elevation of the transmitter shown in Fig. 1, from the sunflower end of the machine; Fig. 6, a vertical cross-section of the transmitter on the line a a of Fig. 4; Fig. 7, a horizontal section through the transmitter-shaft, showing a section of one of the pole-changer-carrying cylinders; Fig. 7^a, a section through the insulating-sleeve, which carries the contact-rings 35 and 36; Fig. 8, a vertical section, on the same scale as Fig. 7, showing a modification in the means for driving the trailer-arm of the sunflower. Fig. 9 is a

In all of the above views corresponding parts are designated by the same figures and letters of reference.

The transmitter has a suitable base A, upon which the parts are mounted. Supported above the base are the key-levers B, pivoted on a rod 3 and retracted by springs 4. Beneath these key-levers are the five tilting bars C, also carried by the rod 3 and retracted by the springs 6. In the case of an individual-key-keyboard machine, such as shown in Fig. 1, a single key-lever is used for each character. In this case each key-lever is provided with teeth 7, as shown in Fig. 6, which coöperate with the tilting bars C, depressing those bars in accordance with the particular permutations which distinguish the particular characters. In the case of a combination-key-keyboard transmitter of the Baudot type only five keys are used, as shown in Figs. 2 and 3, each key being connected to a particular tilting bar and the different permutations being secured by depressing the keys in accordance with the combinations desired. The tilting bars C carry three sets of five downwardly-depending fingers 8. The space-bar 9, which is equivalent to a character, may depress all the tilting bars C. The key-levers

also depress another tilting bar D, which is hung on the rod 3 and moves the escapement-verge 11, which is carried by a rock-shaft 12 and is connected with the tilting bar D by two links 13. The escape-wheel 14 is fixed on the shaft E. This shaft is mounted on the base and is rotated with a step-by-step motion by the escapement. In the particular instance illustrated it is driven by a spring 16, which is secured at its inner end to the shaft and at its outer end to a spring-box 17, which is loose on the shaft. This spring-box is connected by a worm-gear 18 with an electric motor F. The connections between the worm-gear 18 and the motor F may be of any desired character. I illustrate the worm-gear shaft 18^a as having a sprocket-wheel 18^b thereon, the motor-shaft being provided with a corresponding sprocket-wheel 18^c and the two sprocket-wheels being connected together by a sprocket-belt 18^d. The motor serves to wind up the spring. The motor is stopped and started by a circuit-controller operating automatically under the effect of the spring and by means of which an approximately uniform tension of the spring may be maintained. This circuit-controller is composed of a disk 20, which rotates with the shaft and has on its face a spiral groove which has its channel turned abruptly in a direction oblique to the spiral at each turn of the spiral, as illustrated at 21, Fig. 11. This disk 20 is placed opposite the inner face of the spring-barrel 17, and between the two are located two annular plates 22, which are separated by an air-space and are connected in the motor-circuit, so that it is necessary to bridge these two plates to close the motor-circuit. Upon the spring-barrel 17, opposite the disk 20, is pivoted an arm 23, whose central position is maintained by a spring 24. This arm has a pin 25, Fig. 11, which travels in the spiral groove of the disk 20, and it also carries a circuit making and breaking block 26, which plays in and out between the annular plates 22. It will be seen from this that when the spring-barrel runs ahead of the shaft after a certain tension of the spring has been produced the effect will be to advance the pin 25 toward the shaft E in the spiral groove of the disk 20 and to withdraw the block 26 from between the springs 22 and open the circuit to the motor. On the other hand, when the shaft runs ahead of the spring-barrel the effect is to push the arm 23 outwardly and cause the block 26 to bridge the space between the springs 22 and close the motor-circuit. The abrupt shoulders 21 produce a quick break of the circuit, thus preventing the formation of an arc. Upon the shaft E are mounted three drums 27, 28, and 29. Each of these drums carries two sets of pivoted pole-changers 30, five in each set, which when tilted in one position make contact with the positive terminal plates 31 and when tilted in the other position make contact with the negative terminal plates 32, carried by the same drums. (See Fig. 9.)

Carried in grooves along the shaft E are the positive and negative wires 33 34, which are connected, one with all the positive terminals 31 and the other with all the negative terminals 32. These wires extend from insulated contact-rings 35 and 36, carried by the end of the shaft. Springs 37^a and 38^a rest on these rings and connect with the two sources of energy at their positive and negative poles. Two sets of pole-changers are mounted upon each drum, the six sets occupying different points in the rotation of the shaft E, corresponding with the six teeth of the escape-wheel 14, so that one set of the pole-changers will be brought under one set of the fingers 8 of the tilting bars C at each point of rest of the shaft, so as to be shifted from their normal position in contact with the positive terminals 31 to contact with the negative terminals 32. The thirty pole-changers are connected independently with the plates of the sunflower about to be described. This is accomplished by mounting each one of the drums 27 28 29 on the shaft at one end, leaving a space between the drum and the shaft, which is open at the other end of the drum. Into this space projects a spool 37, Fig. 7, which is stationary and is supported by the base, and this spool carries ten insulated metal rings 38, five of which are connected with the pole-changers of one set and five with the pole-changers of the other set on the particular drum by means of spring-pressed plungers 39, which make a rubbing contact with the rings. From the rings 38 wires 40 pass to the sunflower. Stationary combs 41 are mounted on the frame and return the pole-changers of each set to their normal positions after they have been put in connection with the line and just before the pole-changers are again brought into position to be operated upon by the keys.

Surrounding the shaft E, at the opposite end to which it is driven, is the sunflower 42, carrying on its periphery thirty contact-plates 43, which are connected with the wires 40 from the pole-changers. These contact-plates may be in the form of pins supported in insulation. Between the contact-plates 43 are other plates 44, which are connected with the ground. The trailer 45 is insulated from the shaft E and is connected with the line by a spring 46, as shown in Fig. 5. This trailer 45 may be either operated from the shaft E or by means of a separate motor, the former construction being that shown in Figs. 1, 2, 5, and 7 and the latter construction being shown in Fig. 8. With the first form of device the hub of the trailer is connected with a spring-barrel 47, Fig. 7, the inner end of the spring being connected with the shaft E, while the outer end is connected with the spring-barrel 47. The desired normal tension is produced in this spring, which is maintained by a pin 48 on the shaft E. The spring-barrel 47 is connected by a gear which it carries with a pinion on a spindle carrying the fly-wheel 49,

which fly-wheel is connected with the spindle through a pawl and ratchet 50. The shaft E in rotating moves the pin 48 away from its engagement with the spring-barrel 47, and the spring-barrel follows the movement of the shaft under the tension of its spring with a speed which is regulated by the fly-wheel 49, any overthrow of the fly-wheel being permitted by the pawl and ratchet 50. The trailer 10 45 moves with the spring-barrel, and this movement may be a continuous and uniform one, as explained, although the shaft has an intermittent movement. When the trailing arm is driven by a separate motor, it may be 15 operated as shown in Fig. 8, wherein the gear 47' is engaged and driven by a suitable train of gears from a small electric motor E'. The pin 48 will limit the travel of the trailing arm relatively to the shaft E, as will be understood. In order to allow for overthrow of the motor, a simple form of friction-clutch 48' may be interposed between the gear 47' and the hub of the trailing arm.

The circuit connections from the transmitter will be understood by reference to the diagram Fig. 12. In that diagram the double or divided source of energy may be batteries or dynamos, as shown at 51. The wire 52 furnishes the positive impulses, while the wire 30 53 furnishes the negative impulses. These two wires are those which extend to the springs 37^a and 38^a, bearing on the rings 35 and 36 and which are carried by the shaft E. The wires 52 and 53 are thus connected with the wires 33 and 34, carried by the shaft E. These wires 33 and 34 are connected with the positive and negative terminals 31 and 32, with which pole-changers 30 coöperate. The pole-changers 30 are connected (by spring-40 pressed plungers 39, bearing on the rings 38) with wires 40, extending to the contact-plates 43 of the sunflower 42. The line 54 extends from the trailer of the sunflower, being connected with the spring 46. (Shown in Fig. 5.)

45 Referring now to the relay, which is illustrated by Figs. 13 to 16, the permanent magnets 55 support on their outer ends the coils 56, which coöperate with armatures 57, retracted by springs 57'. These armatures are 50 attracted by the permanent magnetism of the magnets 55 when there is no line impulse passing through the coils 56. To restore them to the attracted position quickly and positively after the cessation of the line impulse, 55 I provide the restoring-magnets 58, whose armature-levers 59 pass at their rear ends under the ends of the armature-levers of the magnets 55, so that the attraction of the armatures by the magnets 58 will produce the 60 return of the armatures 57 to their attracted position. One of these relays bridges by the retracted movement of its armature two contacts 60 60. This is the positive relay G or that which responds to positive impulses. 65 The other or negative relay H bridges two sets of contacts 61 and 62. This relay responds to negative impulses.

Referring to Fig. 23 for an explanation of the circuit connections to the relays, it will be seen that the line 54 passes through the 70 coils of both relays, the positive relay G being shown at the top of the figure and the negative relay H at the bottom of the figure. I show the relays connected in series with the line 54; but it will be understood that they 75 may be connected in multiple with the line. The circuit closed at the contact 60 by the positive relay and at the contact 61 by the negative relay is the local circuit which produces the step-by-step mechanical motion of 80 the distributor. The restoring-magnets 58 are also in this circuit. The circuit which is closed by the negative relay at the contact 62 is that which extends through the switch-arm of the distributor to the two sets of selector-magnets, as will be explained.

The distributor, which is illustrated by Figs. 17 to 22, has a vertical shaft 63, which is given a step-by-step motion by the magnet 89 through a pawl and ratchet. The shaft 90 63 carries a switch-arm 64, which travels over a circular range of ten plates 65. It also carries a circuit-closing arm 66 for closing the printing-circuit, which arm connects plate 67 with either of two plates 68 69 to close the 95 printing-circuit through the two divisions of the selector. The distributor-shaft 63 also carries an arm 70, which connects a plate 71 with either of two plates 72 73 for closing the circuit to the restoring-magnets of the two 100 sections of the selector. The automatic restoring device consists of two springs 74, which bear on the ring carried by the shaft of the distributor and insulated therefrom. These two springs when they rest on metal 105 close a circuit to the back point of the armature of the magnet 89, which moves the distributor. This circuit includes a sufficient resistance, so that the current which passes through it from the local battery is less than 110 that which passes through the magnet 89 when its circuit is closed at the contact 60 or 61. Consequently the circuit of the springs 74 has no effect on the magnet 89 during the 115 normal operation of the apparatus; but should the shaft of the distributor stop at some intermediate point other than that where the circuit to the springs 74 will be broken then the magnet 89 will be energized by the current flowing through the springs 74 and 120 through its armature-lever and back contact, and the magnet 89 will become a vibrator and will turn the shaft 63 until the circuit is broken at the springs 74. By including a 125 resistance in the local circuit of the springs 74 the magnet 89 will be affected upon the closure of such circuit with relative sluggishness, and consequently the closing of this local circuit will not affect the correct operation of the magnet 89 by the effect of the line 130 impulses on the relays, which line impulses succeed each other with great rapidity. In this way the switch-arm 64 of the distributor will always be brought to the first plate of

either of the two sets of plates carried by the distributor, notwithstanding the obliteration of one or more of the impulses of a character.

The circuit, which is closed at the contact 5 62 of the negative relay H, passes on one side to the switch-arm 64 of the distributor, and on the other side is divided into two branches, one of which extends to the selector-magnets 75, and the other of which extends to the 10 other set of selector-magnets 76. From the two sets of selector-magnets wires pass to the ten plates 65 of the distributor, the wires from the selector-magnets 75 occupying the five plates on the one side of the distributor, 15 and the wires from the other set of the selector-magnets 76 occupying the five plates on the other side of the distributor. The operation of the relays, therefore, (see Fig. 23,) 20 is as follows: Each time the positive relay operates it simply advances the distributor one step, moving the switch-arm 64 from one plate 65 to the succeeding plate without affecting the selector-magnets. When the negative relay operates, however, it not only advances the distributor one step, (by closing the local circuit at the contact 61,) but at the same time closes the circuit to the selector-magnet, which is connected to the plate upon 25 which the switch-arm of the distributor stands 30 at the moment of the operation.

The selector, one division of which is illustrated particularly by Figs. 24 to 28, is composed of two divisions, each of which is a frame supporting thirty-one series of plates 35 77, each series being composed of six plates, between the adjoining ends of which are five breaks in the circuit. The plates of the thirty-one series are connected together at one end by a cross-bar 78, and are separately connected at the other end to wires 79, leading to the printing-magnets. Mounted beneath the plates 77 and extending parallel with each of the five breaks between the plates referred to is an insulating block or segment 80, each 40 carried on a rock-shaft 81. Keyed to one end of each of said rock-shafts is a lever 82, carrying an armature 83 at its lower end, said armature being attracted by one of the selector-magnets 75 or 76. A link 84, having 45 slots 85 therein, in which work pins 86, carried by levers 82^a, is employed for the purpose of restoring the insulating blocks or segments 80 to their normal positions. To effect this, a restoring-magnet 87 is employed, the 50 armature 87^a of which is connected to the link 84, said armature being normally retracted by a spring 88. The levers 82^a project downward from each of the rock-shafts 81 at about the center thereof. When, therefore, 55 one or more of the shafts 81 are rocked by the attraction of the armatures of the selector-magnets, the pins 86 on the levers 82^a will move in the slots 85, and when the restoring-magnet 87 is energized it will attract 60 the armature 87^a, moving the bar 84 and engaging the pins 86 on those shafts 81 which were rocked to restore them to their normal

positions. When the shafts 81 are thus restored, the magnet 87 will be deenergized and the bar 84 will be returned by the action 70 of the spring 88, the slots 85 allowing for this return movement with respect to the pins 86 without moving the latter. The insulating blocks or segments 80 carry in line with each of the plates 77 metal plates 89, some of 75 which close the breaks on the attracted position of the segments, while others close the breaks on the unattracted position of the segments. For instance, when the key lettered Q in Fig. 1 is depressed it will shift the first 80 pole-changer of the set on which it acts from positive to negative. The result will be that the first insulating-segment of the selector (the top one in Fig. 24) will be moved, and the circuit through the first set of selector-springs, and no other, will be closed. If the second key, or that lettered W in Fig. 1, is depressed, only one pole-changer will be shifted from positive to negative and that will be the second pole-changer. That will produce the movement of the second insulating-segment of the selector, which will close the circuit through the second set of contact-plates 77. If the third key (lettered E) is depressed, it will shift the first and second pole-changers from positive to negative. This will move the first and second cross-bars of 90 the selector and will close the circuit through the third set of springs. It will not close the circuit through either the first or second set 100 of contact-plates, however, because it will break the first set of contact-plates at the second segment and the second set of contact-plates at the first segment. In this way the numerous permutations produced by the keys 105 at the transmitter are utilized to close one path, and one path only, for each character through the selector.

Having reference particularly to Figs. 27 and 28, and representing the positive impulses by the letter P and the negative impulses by the letter N, the several permutations by which any one of the thirty-one paths of the selector will be established will be as follows:

1..	N	P	P	P	P	P	17..	N	P	P	P	N
2..	P	N	P	P	P	P	18..	P	N	P	P	N
3..	N	N	P	P	P	P	19..	N	N	P	P	N
4..	P	P	N	P	P	P	20..	P	P	N	P	N
5..	N	P	N	P	P	P	21..	N	P	N	P	N
6..	P	N	N	P	P	P	22..	P	N	N	P	N
7..	N	N	N	P	P	P	23..	N	N	N	P	N
8..	P	P	P	N	P	P	24..	P	P	P	N	N
9..	N	P	P	N	P	P	25..	N	P	P	N	N
10..	P	N	P	N	P	P	26..	P	N	P	N	N
11..	N	N	P	N	P	P	27..	N	N	P	N	N
12..	P	P	N	N	P	P	28..	P	P	N	N	N
13..	N	P	N	N	P	P	29..	N	P	N	N	N
14..	P	N	N	N	P	P	30..	P	N	N	N	N
15..	N	N	N	N	P	P	31..	N	N	N	N	N
16..	P	P	P	P	N	N						

In other words, these permutations, stated with reference to the pole-changers which are

shifted from positive to negative, will be for a series of five characters, as follows: 1, 2, 1 2, 3, 1 3, 2 3, 1 2 3, 4, &c., the figures in each case representing the particular pole-changers 5 of a set of five, which are shifted from positive to negative. The diagram Fig. 29 indicates this arrangement in connection with the two divisions of the selector, each line representing a vertical set of plates, being 10 shown as broken at the one or more points where the circuit through that line is normally broken and where it must be closed to produce a closure of the circuit. The wires 79 of the two divisions of the selector extend to 15 thirty-one small magnets 90, each one of these magnets being connected with a corresponding set of plates of the two divisions of the selector. These magnets are connected to a common return-circuit to the printing-magnet 91, which extends through the local battery to the plate 67 on the distributor. From 20 the plates 68 and 69 of the distributor two connections are made to the selector-plates of the two divisions of the selector, all as illustrated in Fig. 29.

Each of the small magnets 90 may operate a type-bar or any other suitable device as is common in electric type-writers, or they may be used for operating other elements of a machine or device to be controlled. I prefer, however, to adopt the arrangement illustrated in Figs. 30 and 31, wherein the printing mechanism consists, essentially, of the printing-magnet 91, which operates on a cross-bar 92, which in its movement depresses the particular one of the printing-levers 93 whose hook 94 is drawn under the bar 92 by the magnet 90.

In the above description I have outlined the 40 operation of the several devices as the description thereof has proceeded, so that a detailed explanation of the operation of the system is unnecessary.

Having now described my invention, what 45 I claim as new, and desire to secure by Letters Patent, is as follows:

1. In a telegraph system, a keyboard-transmitter having two or more sets of pole-changers acted on successively by the keys, 50 and means for bringing the sets of pole-changers into connection with the main line subsequent to the operation thereof by the keys, substantially as set forth.

2. In a telegraph system, a keyboard-transmitter having two or more sets of rotating pole-changers acted on successively by the keys, and means for bringing the sets of pole-changers into connection with the main line subsequent to the operation thereof by the 55 keys, substantially as set forth.

3. In a telegraph system, a keyboard-transmitter having two or more sets of pole-changers acted on successively by the keys, and a circuit-controller adapted to bring the 60 sets of pole-changers successively into connection with the main line, whereby a set of

pole-changers will be under the action of the keyboard while another set is in connection with the line, substantially as set forth.

4. In a telegraph system, a keyboard-transmitter having two or more sets of pole-changers acted on successively by the keys, in combination with a movable circuit-controller for connecting the sets of pole-changers successively with the line, said circuit-controller having a retarded movement, whereby the rate at which the keyboard is operated may be different from that at which the impulses are delivered to the line, substantially as set forth. 70

5. In a telegraph system, a keyboard-transmitter having two or more sets of rotating pole-changers rotated with an intermittent movement and brought successively into position to be acted on by the keys, in combination with a rotating circuit-controller for connecting the sets of pole-changers successively with the line, said circuit-controller being driven with a substantially continuous rotary motion, substantially as set forth. 80

6. In a telegraph system, a keyboard-transmitter having two or more sets of rotating pole-changers rotated with an intermittent movement and brought successively into position to be acted on by the keys, in combination with a rotating circuit-controller for connecting the sets of pole-changers successively with the line, said circuit-controller deriving its motion from the intermittently-rotating shaft which drives the pole-changers, but connected therewith so as to have a continuous rotary motion, substantially as set forth. 90

7. In a telegraph system, a keyboard-transmitter having two or more sets of rotating pole-changers driven by a shaft having a step-by-step movement, a sunflower and trailer connecting the sets of pole-changers successively with the line, said trailer being connected with the intermittently-rotating shaft through a spring and being retarded in its motion by a fly-wheel, whereby the trailer will be given a uniform rotary motion, substantially as set forth. 105

8. In a telegraph system, the combination with a keyboard-transmitter having an intermittently-rotating shaft, of a sunflower and trailer connecting the transmitter with the line, a spring connecting the trailer with the intermittently-rotating shaft, a fly-wheel turning with the trailer and retarding its movement, and means for permitting the advance movement of the fly-wheel independent of the trailer, substantially as set forth. 115

9. In a telegraph system, a keyboard-transmitter wherein the movement of any key or combination of keys shifts the pole-changers of a set in accordance with a predetermined permutation, having in combination two or more sets of pole-changers rotating in the same plane and brought successively into position to be operated upon by the keys, substantially as set forth. 125

10. In a telegraph system, a keyboard-transmitter wherein the movement of any key or combination of keys shifts the pole-changers of a set in accordance with a predetermined permutation, having in combination two or more sets of pole-changers movable in separate paths successively into position to be operated upon by the keys, and a number of tilting bars common to all the keys and having two or more sets of fingers located to operate upon the two or more sets of pole-changers, whereby each key when depressed will act upon one of the two or more differently-located pole-changers, substantially as set forth. 15

11. In a telegraph system, a keyboard-transmitter wherein the movement of any key or combination of keys shifts the pole-changers of a set in accordance with a predetermined permutation, having in combination two or more sets of pole-changers rotating in the same plane, and two or more other sets of pole-changers rotating in another plane, said four or more sets of pole-changers being brought successively into position to be operated upon by the keys, substantially as set forth. 20

12. In a telegraph system, a keyboard-transmitter having two or more sets of rotating pole-changers mounted upon one or more drums, two positive and negative connections running to the movable elements of the pole-changers and rotating therewith, a set of positive plates and a set of negative plates revolving with each set of pole-changers and connected in the circuit by the shifting of the pole-changers, a line-sunflower and a rubbing contact between each of said terminals connected with a stationary conductor extending to the line-sunflower, substantially as set forth. 25

13. In a telegraph system, a keyboard-transmitter wherein the movement of any key or series of keys shifts the pole-changers of a set in accordance with a predetermined permutation, having in combination two or more sets of pole-changers movable successively into position to be operated upon by the keys, and means for shifting the pole-changers of each set to their normal position before they are brought under the action of the keys, substantially as set forth. 30

14. In a telegraph system, a keyboard-transmitter wherein the movement of any key or series of keys shifts the pole-changers of a set in accordance with a predetermined permutation, having in combination two or more sets of pole-changers movable successively into position to be operated upon by the keys, and one or more stationary combs for shifting the pole-changers of each set to their normal position before they are brought under the action of the keys, substantially as set forth. 35

15. In a telegraph system, a keyboard-transmitter wherein are combined two or more ro-

tating pole-changers acted upon successively by the keys, a shaft for driving the pole-changers, an escapement operated by the keys for giving the shaft a step-by-step movement, and a source of power for driving the shaft connected with the shaft through a spring, substantially as set forth. 70

16. In a telegraph system, a keyboard-transmitter having in combination two or more rotating pole-changers acted upon successively by the keys, an escapement moved by the keys for giving the pole-changers an intermittent motion, a rotary electric motor for driving the pole-changers, a spring connection between the motor and pole-changer shaft, and an automatically-acting circuit-controller for opening and closing the circuit to the motor arranged to maintain an approximately uniform stress upon the spring, substantially as set forth. 75

17. In a telegraph system, the combination with a transmitter transmitting different characters by permutations of a number of impulses of opposite polarity, of a double relay composed of two permanent magnets operated, one by impulses of one polarity, and the other by impulses of the other polarity, and restoring-magnets in a local circuit for restoring the relay-armatures to their attracted position, substantially as set forth. 80

18. In a telegraph system wherein the characters are distinguished by permutations of a number of impulses of opposite polarity, the combination with the line and the relay, of a receiving-distributer having a plurality of sets of distributing-plates, each distributing the impulses of a single character and operating successively, whereby the impulses representing successive characters will be distributed to the receiving apparatus through different circuits, and a receiving apparatus having sections corresponding in number to the sets of distributing-plates, each section receiving the impulses of a single character from one of said sets of distributing-plates, substantially as set forth. 90

19. In a telegraph system wherein the characters are distinguished by permutations of a number of impulses of opposite polarity, the combination with the line and the relay, of a receiving-distributer having two sets of distributing-plates, each receiving the impulses of a single character and operating successively, whereby the impulses representing successive characters will be distributed to the receiving apparatus through different circuits, and one or more other circuit-controllers operated by the distributer and controlling circuits to the receiving apparatus corresponding to the two sets of distributing-plates, such additional circuits being closed for one set of distributing-plates, while the other set of distributing-plates is in action, substantially as set forth. 100

20. In a telegraph system wherein the char-

105

95

110

115

120

125

130

- acters are distinguished by permutations of a number of impulses of opposite polarity, the combination with the main line, of a receiving apparatus divided into a plurality of parts, 5 and means for bringing the parts into action simultaneously for different purposes and successively for the same purpose, whereby the entire time will be utilized in the operation of the receiving apparatus, substantially as set forth.
21. In a printing-telegraph system wherein the characters are distinguished by permutations of a number of impulses of opposite polarity, the combination with the main line, of 10 a receiving selecting apparatus divided into a plurality of parts, each part controlling the selection and printing of the characters, the parts being so organized that while one is controlling the printing, another part is controlling the selection for the next letter, and means for operating one part to control the printing and for simultaneously operating another part to control the selection for the next letter, and vice versa, substantially as 15 set forth.
22. In a telegraph system wherein the characters are distinguished by permutations of a number of impulses of opposite polarity, a selector composed of a number of sets of 20 plates, each set having breaks at a number of points corresponding with the number of impulses constituting a character, circuit-closers coöperating with said plates, a portion of said circuit-closers normally closing the breaks with which they coöperate, and the other circuit-closers normally opening the breaks with which they coöperate, and means for shifting the said circuit-closers by impulses of one polarity, whereby any desired 25 permutation of the given number of impulses will establish a single path through the selector, substantially as set forth.
23. In a telegraph system wherein the characters are distinguished by permutations of 30 a number of impulses of opposite polarity, the combination with the main line and the relay, of a distributor divided into two parts, a selector divided into two parts, the distributor distributing the impulses to the two parts of 35 the selector alternately, and printing-circuits controlled by the distributor through the two parts of the selector, the printing-circuit for one part of the selector being closed at the distributor, while the character impulses are being distributed to the other part of the selector, substantially as set forth.
24. In a telegraph system wherein the characters are distinguished by permutations of 40 a number of impulses of opposite polarity, a selector composed of a number of sets of plates, each set being broken at a number of points corresponding with the number of character impulses, insulating-segments carrying contact-plates bridging the breaks in 45 the different sets, magnets moving said seg- 50 ments separately, and a restoring-magnet for restoring all the segments to their normal position, substantially as set forth.
25. In a telegraph system wherein the characters are distinguished by permutations of a 55 number of impulses of opposite polarity, the combination with the main line and the relay, of a two-part distributor, a two-part selector, the distributor distributing the impulses to the two parts of the selector alternately, a circuit-controller moved by the distributor for closing the circuit alternately through the two parts of the selector, the printing-circuit for one part of the selector being closed at the distributor while the character impulses are 60 being distributed to the other part of the selector, restoring-circuits and a circuit-controller moved by the distributor for closing the restoring-circuits, substantially as set forth.
26. A system of telegraphy wherein are combined a keyboard-transmitter acting to produce permutations successively in a number of sets of pole-changers having an intermittent rotary motion, a sunflower and trailer for distributing the sets of impulses successively to the line and having a continuous rotary motion so as to distribute the intermittently-produced permutations continuously and with approximate uniformity to the line, 65 a single line-wire receiving the character impulses, and a receiving apparatus including selecting mechanism and operating mechanism, the selecting mechanism being divided into two parts which are acted on alternately by the character impulses, and the operating mechanism being operated through one part of the selector while the permutations corresponding to a character are being established in the other part of the selector, substantially as set forth.
27. A system of telegraphy wherein are combined a keyboard-transmitter acting to produce permutations successively in a number of sets of pole-changers having an intermittent rotary motion, a sunflower and trailer for distributing the sets of impulses successively to the line and having a continuous rotary motion so as to distribute the intermittently-produced permutations continuously and with approximate uniformity to the line, 70 a single line-wire receiving the character impulses, a double relay controlling two local circuits, a distributor having two sets of distributing-contacts and also carrying a circuit-controller controlling the printing-circuits, and a circuit-controller controlling the circuits to the selector-restoring magnets, a selector made in two parts in which the character permutations are alternately established by the distributor and in which the printing and restoring circuits are operated for one division of the selector, while the permutations are being established in the other division of the selector, and a printing mechanism comprising a series of selecting-magnets,

one for each type, and a printing-magnet which moves the types selected, the said printer-selecting magnets being located in branches from both divisions of the selector, and the 5 printing-magnet being located in a common return to said branches, substantially as set forth.

This specification signed and witnessed this 17th day of January, 1898.
